MODULAR AUTOMATIC ELECTROPLATING EQUIPMENT

Rudolf John Garbely, Bloomfield, and Anthony R. Diorio, Wayne, N.J., assignors to Sel-Rex Corporation, Nutley, N.J.

Filed May 7, 1968, Ser. No. 11,813

Term of patent 14 years

The portion of the term of the patent subsequent to Sept. 27, 1984, has been disclaimed

Int. Cl. D15—09

U.S. Cl. D26—1 N

FIG. 1

FIG. 2

FIG. 3

FIG. 4

FIG. 5

FIG. 6

FIG. 7

FIG. 1 is a perspective view of the modular automatic electroplating equipment of the present invention.

FIG. 2 is a top plan view of the equipment shown on FIG. 1.

FIG. 3 is a front elevational view of the equipment shown in FIG. 1.

FIG. 4 is a bottom plan view in the equipment shown in FIG. 1.

FIG. 5 is a rear elevational view of the equipment shown in FIG. 1.

FIG. 6 is a left side elevational view of the equipment shown in FIG. 1.

FIG. 7 is a right side elevational view of the equipment shown in FIG. 1.

We claim:

The ornamental design for a modular automatic electroplating equipment, substantially as shown and described.
